(57) **CLAIM**

The ornamental design for a console for automobiles, as shown and described.

DESCRIPTION

FIG. 1 is a top plan view of the console for automobiles; FIG. 2 is an enlarged top plan view thereof, taken from area 2 in FIG. 1;

FIG. 3 is a top, front, and left side perspective view of the console for automobiles of FIG. 1; and,

FIG. 4 is a top, rear, and left side perspective view thereof. The dash-dot broken lines illustrate portions of the console for automobiles which form no part of the claimed design. The dash-dot broken lines define the boundaries of the claimed design and a lead line of the enlarged view area, and form no part of the claimed design.
